UNITED STATES PATENT OFFICE.

CHARLES M. FITCH, OF KANKAKEE, ILLINOIS, ASSIGNOR TO SEARS, ROEBUCK AND CO., OF CHICAGO, ILLINOIS, A CORPORATION OF NEW YORK.

WICK OIL BURNER.

Application filed February 16, 1927. Serial No. 168,488.

The invention relates to liquid fuel burners, more particularly of the tubular wick feed type commonly employed in oil stoves, and to the means for intermixing air with 5 the distilled gas for supporting combustion.

It is the principal object of the invention to produce in an oil burner of the character referred to, an improved intermixture of air with the gas distilled from the fuel oil, 10 by controlling the relative volume and direction of flow so as to accomplish complete combustion of the fuel with a maximum of heat generated therefrom.

Other objects and advantages will be apparent in the following detailed description of the preferred embodiment of the invention illustrated in the accompanying drawings, in which:

Figure 1 is an elevation partially in section of a portion of an oil burner illustrating the parts controlling the supply of air to the burner flame.

Fig. 2 is a plan view of the parts shown in Fig. 1, with the chimney removed.

Fig. 3 is a bottom view with the chimney and draft sleeve removed.

Fig. 4 is an enlarged sectional elevation of a fractional portion of the parts immediately associated with the flame supporting end of the wick, and in which arrows are diagrammatically used to indicate the movement of the air currents in relation to the wick as controlled by the burner structure.

With reference to the drawings, the burner structure comprises a pair of spaced concentric tubes 1 and 2 between which is supported a wick 3 of suitable fabric, the lower end of the latter being submerged in a supply of oil maintained in the chamber formed by the lower end closure of the space between the tubes 1 and 2, the oil being supplied through a communicating pipe connection 4. The wick 3 may be adjustably positioned longitudinally of the tubes by means of a cylindrical shell 5 movably positioned between the tubes 1 and 2, and suitably secured to the wick. The shell 5 is provided with diagonally arranged series of perforations 6 which are adapted for engagement by a toothed pinion 7 fixed upon a rotatable shaft 8 carrying a turning knob 9. The pinion and shaft are suitably supported on the outer tube 2 preferably within a housing 50

10. Rotation of the pinion 7 effects a spiral

movement of the shell 5 to raise or lower the wick. The ends of the inner wick supporting tube are open to permit the passage therethrough of air to the burner flame.

A deflector plate 11 is positioned adjacent the upper end of the wick 3 and its supporting tubes. The plate 11 preferably has a series of small air passages 12 opening therethrough, and has a downwardly inclined marginal portion 13 of which the periphery is spaced longitudinally from the end of the wick.

The deflector plate 11 is supported in position by means of a plurality of wings 14 suitably secured to the plate and extending inwardly of the inner wick supporting tube 1. An annular plate 15 preferably is fixed upon the inner tube 1 and spaced from the upper end thereof to support the lower ends of the wings 14. The annular plate 15 is provided with spaced notches 16 through which pass hook portions 17 of the wings, in the lowering of the latter. By turning the wings the hooks 17 become engaged beneath the plate 15 to secure the wings and deflector plate in position.

The annular plate 15 is provided intermediately of the notches 16 with upwardly extending guiding lobes 18 which facilitate the positioning and locking of the deflector plate and its supporting wings by guiding the hook portions 17 into the notches 16 when the wing structure is introduced into the end of the wick supporting tube 1. When the wings 14 are in normal position of 90 supported abutment upon the upper side of the plate 15, the hooks 17 are spaced substantially below the plate 15. Upon turning up the wick to an extreme height, with the spiral movement previously described, 95 the wick engages the deflector plate and lifts the latter with the wings 14. The rotative movement of the wick swings the hooks 17 out of register with notches 16 before the hooks reach the plate 15, and cause the hooks 100 to engage the latter, thereby limiting the upward movement of the deflector plate and of the wick and preventing the elevation of the wick to an extent producing a dangerous flame. This locking action occurs automatically whether or not care has been taken to turn the wings and hooks into locked position when the deflector plate and wing structure is inserted within the tube 1.

The wings 14 also carry a cylindrical band 110

19 positioned adjacent the inner wick tube 1 and extending outwardly therefrom with an inwardly inclined terminal portion 20. The band 19 is positioned closely adjacent to 5 the inner tube 1 for the maximum radiation of heat, transmitted from the flame through the deflector plate and its supporting wings, against the wick supporting inner tube, thereby aiding the distillation of gas from 10 the liquid oil with which the wick is saturated.

Encompassing the outer wick tube 2 is a draft sleeve 21 positioned in concentric spaced relation to the wick tube 2. The 15 lower portion of the sleeve 21 may be reinforced by an annular member 22 which preferably is formed with inwardly extending radial lugs 23 bearing upon an annular collar 24 fixed upon the outer wick tube 2 and 20 which serves to support the draft sleeve in position. The upper portion of the sleeve 21 is provided with an inner annular flange forming a wide shoulder 25. Preferably this shoulder is formed in the sleeve structure 25 with its under surface substantially horizontal, and extends half way or more across the space between the sleeve and the outer wick tube. The inner periphery of the shoulder 25 is positioned in spaced relation laterally and above the upper end of 30 the outer wick tube 2, and also in spaced relation to the periphery of the inclined marginal portion 13 of the deflector plate. There is preferably provided above the 35 shoulder 25 an outwardly flared terminal portion 26 of the draft sleeve extending somewhat above the periphery of the inclined flange 13.

Supported on a suitable shoulder 27 40 formed in the lower portion of the sleeve 21 is a bottom plate 28 preferably of arched cross section and outwardly carrying an upwardly extending cylinder 29 functioning as a chimney for the burner flame. The bottom plate 28 may have perforations therein to admit air to the base of the chimney. The chimney and its bottom plate are preferably removable by upward withdrawal 45 from the shoulder 27, and the draft sleeve is also preferably removable by upward withdrawal from the outer wick tube abutment 50 collar 24.

In operation, the deflector plate 11 with 55 its inclined marginal portion 13, and the draft sleeve 21 with its inwardly turned shoulder 25 are so arranged in relation to the flame supporting end of the wick 3, that the air currents passing upwardly within the inner wick tube 1 and between the outer 60 wick tube 2 and the draft sleeve 21 meet across the end of the wick 3 in substantially diametrically opposed direction of movement in an approximately horizontal plane. The air currents are thus thoroughly inter- 65 mixed in the zone immediately above the

end of the oil saturated wick from which the gas is being distilled by the heat of the burner flame. This directly opposed cross movement of the two air currents through the gas filled zone immediately above the 70 wick, as indicated by the arrows in Fig. 4, accomplishes complete and uniform intermixture of the gas and air in the proper proportion to support complete combustion of the gas. The combustible mixture then 75 flows through the aperture between the deflector plate and the draft sleeve, where it is consumed in a blue flame as illustrated at 30.

The temperature of the air entering the 80 mixing zone is raised as to the outer current by heat radiation from the hot draft sleeve 21. The inner air current arises against the hot deflector plate 11 and therefrom into the mixing zone. The movement of the inner air current across the under face of the deflector plate with consequent raising of 85 temperature is further effected by means of the inwardly inclined terminal portion 20 of the band 19.

The advantages of complete and uniform intermixture of the air with the distilled gas is accomplished by the substantially diametric opposition of the air currents entering the mixing zone at the base of the 90 flame, and is effected by the sharp inward turn of the outer current by the draft sleeve shoulder 25 which is so positioned in relation to the inclined marginal portion 13 of the deflector plate that the meeting air currents flow directly toward each other into the gas mixing zone. In the ordinary structures, wherein the outer current arises substantially vertically into the flame, there is an outer blanket of air in which the gas is 100 too dilute to form the hot blue flame necessary for maximum heat, and results in the loss of efficiency in the flame. In applicant's construction the directly opposed air currents flow through each other, causing 105 uniform intermixture of the gas with all of the air admitted to the flame, and it has been found that this arrangement produces a flame of maximum intensity and heating 110 efficiency.

I claim as my invention:

1. An oil burner having, in combination, with a tubular wick and a pair of concentric tubes between which said wick is guided for up and down movement, an annular member mounted concentrically within the inner wick tube and having its upper end terminating in a plane above the wick, a plate supported to extend above the upper end of said member in spaced relation thereto, said member and plate defining an annular slot through which air rising through the annular member is discharged outwardly in a substantially horizontal direction, an annular member encircling the outer wick 115 120 125 130

tube and spaced a substantial distance therefrom to form an outer air passage, said outer member having an annular flange of substantial width projecting inwardly substantially in the plane of the lower edge of said slot and spaced upwardly from the upper end of the outer wick tube, said flange being disposed above the upper end of the outer wick tube and serving to deflect the air current rising in said outer passage inwardly in direct opposition to the air current discharging through said slot, whereby to effect an intimate mixture of the two air currents with fuel vapor rising from the wick at a point immediately above the wick, said outer annular member having an upwardly and outwardly inclined portion above said deflecting flange spaced from the periphery of said plate.

20 2. In an oil burner, the combination of a pair of spaced concentric tubes adapted to support a wick therebetween, the inner of said tubes forming an air passage, a substantially plane deflector plate positioned endwardly of said tubes having its marginal portion inclined toward said wick with its periphery spaced endwardly opposite to said wick, a sleeve spaced concentrically outward of said outer wick tube to form an air passage therebetween, and a part projecting inwardly from said sleeve to a point substantially above and spaced from the upper end of the outer wick tube, said part providing an abrupt deflecting shoulder, the marginal portion of said deflector plate and said deflecting shoulder being arranged to direct the deflected air currents respectively passing thereby in substantially diametrical opposition for intermixture contiguous to the end of said wick.

3. In an oil burner, the combination of a pair of spaced concentric tubes adapted to support a wick therebetween, the inner of said tubes forming an air passage, a band removably supported within said inner tube having an inwardly inclined terminal portion adjacent the end of said wick, said band being positioned closely adjacent said inner tube, a deflector plate positioned endwardly of said tubes having its marginal portion inclined toward said wick with its periphery spaced endwardly opposite to said wick, a sleeve spaced concentrically outward of said outer wick tube to form an air passage therebetween, and a substantially horizontal deflecting flange of substantial width carried by said sleeve and extending inwardly toward said wick in spaced relation to the end thereof and spaced from the periphery of said deflector plate but in substantially

the same horizontal plane above the wick, and an outwardly flared flange rising from the inner periphery of said deflecting flange the marginal portion of said deflector plate and said deflecting flange being effective to direct the deflected air currents respectively passing thereby in substantially diametrical opposition for intermixture at a point immediately above the wick with the distilled gas arising from said wick.

4. In an oil burner, the combination of a pair of spaced concentric tubes adapted to support a wick therebetween, a deflector positioned endwardly of said tubes in spaced relation to said wick, wings supporting said deflector and extending inwardly of said inner tube, hooks on the inner ends of said wings, an annular plate secured upon said inner tube in position for supporting said wings, said plate having notches for the passage therethrough of said hooks, and upwardly extending guiding lobes mounted on said plate intermediately of said notches adapted to guide said hooks into said notches.

5. In an oil burner, the combination of a pair of spaced concentric tubes adapted to support a wick therebetween, a deflector positioned endwardly of said tubes in spaced relation to said wick, wings supporting said deflector and extending inwardly of said inner tube, hooks on the inner ends of said wings, an annular plate secured upon said inner tube in position for supporting said wings, said plate having notches for the passage therethrough of said hooks, said hooks being normally positioned substantially below said plate, and means for elevating said wick with a spiral movement, said wick engaging said deflector at the upper portion of its range of movement and imparting a rotative motion thereto whereby said hooks are moved out of register with said notches and into locking abutment with said plate.

6. In an oil burner, the combination of a pair of spaced concentric tubes adapted to support a wick therebetween, a deflector plate positioned endwardly of said tubes in spaced relation to said wick, means for raising and lowering the wick adapted to impart a rotational movement thereto, and a device for disengageably connecting said plate to the inner wick tube so as to limit the upward travel of the wick, said device being automatically operable as the wick is raised to render said connection effective.

In testimony whereof, I have hereunto affixed my signature.

CHARLES M. FITCH.
